Patented June 5, 1917.

UNITED STATES PATENT OFFICE.

OTTO MUELLER, OF RICHMOND, CALIFORNIA.

BRACKET.

1,228,583.

Specification of Letters Patent. Patented June 5, 1917.

Application filed March 4, 1916. Serial No. 82,089.

To all whom it may concern:

Be it known that I, OTTO MUELLER, a citizen of the United States, residing at Richmond, in the county of Contra Costa, State 5 of California, have invented a new and useful Bracket, of which the following is a specification, in such full and clear terms as will enable those skilled in the art to construct and use the same.

10 This invention relates to a bracket for supporting a typewriter, plates or books as may be desired, and its object is to produce a simple and strong form of bracket having considerable strength which can be swung 15 from one position to another to suit the convenience of the user.

Another object of the invention is to produce a bracket which can be easily changed from one position to another according to 20 the desires of the user, only two screw eyes being required to support the bracket.

Another object of the invention is to provide means whereby the bracket may be fixed in one position or another as may be 25 desired by the user.

An embodiment of the invention is shown in the drawing in which the same reference numeral is applied to the same portion throughout, but I am aware that there may 30 be many modifications thereof.

Figure 1 is a side elevation of the complete bracket as it appears when in use as a stand secured to the side of a wall,

Fig. 2 is a side elevation of the complete 35 bracket as it appears when used on the side of a desk as a stand for a typewriter,

Fig. 3 is a plan view of the complete stand,

Fig. 4 is a perspective view of the stand as 40 used in connection with a bed for the support of cups or glasses,

Fig. 5 is a view in plan of the clamp used for connecting the stand to the legs of a bed, and

45 Fig. 6 is a perspective view of a bracket without the side braces shown in the previous figures.

The numeral 1 represents a wall in which 50 two screw eyes 2 and 3 have been placed for the support of the bracket. The bracket comprises a tubular vertical member which is integral with a flat horizontal member 4. The tubular member has an opening entirely therethrough to receive a rod 5 to connect 55 it to the two screw eyes and it is provided with two lugs 6 and 7.

The tubular member 3 and horizontal piece 4 are integral with each other and the tube is formed up so that it has a slot at its joined edges as indicated at 8 in Fig. 6. In order to brace the top piece 4 a plate 9 is connected with the ears 6 and 7 and with the outer end of the plate 4, while two braces 10 and 11 connect the lower portion of the plate 9 with the top of the stand 12 to prevent it from bending sidewise.

When the stand is used in conjunction with a desk a screw eye 14 may be inserted in the lower portion of the desk 15 while in the desk cover 16 a hole is bored at the 70 corner to receive the rod 5, said hole being placed in such a position as to enable the stand 12 to be turned in front of the desk or turned back entirely out of the way at the 75 end of the desk as may be desired.

When it is desired to use the stand in conjunction with a bed a pair of clamps 17 and 18 may be used. Said clamps each have a large eye 19 and a smaller eye 20 to receive the rod 5, while a screw 21 is used to draw 80 the clamps up tightly on the bed leg 22. The clamps may be placed at any suitable height from the floor at the convenience of the user.

In the form of the invention shown in Fig. 6 the parts are substantially identical 85 with the form of the invention shown in the other figures, save that the bracket is provided with only one brace.

An advantage of this bracket lies in the 90 fact that it is very easily connected to or disconnected from any wall or other place where it may be used by simply removing two screws, as well as in the fact that it is movable thereby enabling a stand or other top carried thereby to be moved from one 95 position to another as may be demanded.

The lugs 6 and 7 are made long enough so that they provide room for a pivot pin for the lever 23, said lever having an eccentric portion 23' which bears on the rod 5 to hold the bracket or stand in a fixed position with respect to said rod, and inasmuch as said rod may be provided with a squared portion at 24 or may be otherwise so shaped as to hold its position with respect to the eyebolts in which it is placed, the bracket or stand is fixed in position as may be desired by the user by simply depressing the lever 23 to the position shown in the figures.

Having thus described my invention what 110 I claim as new and desire to secure by Letters Patent of the United States, is as fol-

lows, express reservation being made of permissible modifications thereof:

1. A bracket comprising a tubular standard, a pin adapted to pass through the tubular standard for connecting the bracket to suitable supports, an integral horizontally extending member connected with the tubular standard, a stand top connected to the horizontally extending member, and braces connected to said stand top and to the first brace on each side of the horizontally extending member.
- 10 2. A bracket comprising a tubular stand-

ard, a pin adapted to pass through the tubular standard for connecting the bracket to 15 suitable supports, an integral horizontally extending member connected to the tubular standard, a brace connected to the tubular standard and the horizontally extending member, and an eccentric lever for locking 20 the position of the bracket with respect to the supporting pin therefor.

In testimony whereof I have hereunto set my hand this 26th day of February, A. D. 1916.

OTTO MUELLER.
